(57) CLAIM

The ornamental design for a convertible leaning post seating for marine vessels, as shown and described.

DESCRIPTION

FIG. 1 is a rear perspective view of a convertible leaning post seating for marine vessels.

FIG. 2 is a side view thereof;

FIG. 3 is an opposite side view thereof;

FIG. 4 is a front view thereof;

FIG. 5 is a rear view thereof;

FIG. 6 is a top view thereof; and,

FIG. 7 is a bottom view thereof.

The broken lines are for the purposes of illustrating portions of the convertible leaning post seating that form no part of the claim.

1 Claim, 7 Drawing Sheets
